UNITED STATES PATENT OFFICE.

ALEXANDER W. MARR, OF CANTON, OHIO.

QUICK-ACTION DOUBLE-GEAR JACK.

1,423,671.

Specification of Letters Patent. Patented July 25, 1922.

Application filed October 8, 1920. Serial No. 415,620.

To all whom it may concern:

Be it known that I, ALEXANDER W. MARR, a citizen of the United States, residing at Canton, in the county of Stark and State of Ohio, have invented certain new and useful Improvements in Quick-Action Double-Gear Jacks, of which the following is a specification.

The principal object of my invention is 10 to provide a simple, strong and efficient quick-action double-gear jack by which so great a load as a five-ton automobile truck may be speedily lifted with a minimum of effort.

Another object of the invention is to provide a lifting bar whose teeth are interstepped or made zigzag to increase the strength of the bar and the lifting power of the jack.

It is still another object of my invention to provide ball and socket means to permit the plunger-carrying slide to be released from its upper and lower positions by a blow from the jack handle or other instrument.

Another object of the invention is the provision of pawls and gears for the jack, that are constructed of laminations to cheapen its construction.

It is still another object of my invention 30 to provide plungers that are secured to the slide, and not to the pawls which they press into engagement with the teeth of the lifting bar as shown in my Patent No. 1,257,508 granted February 26th, 1918.

Other important and incidental objects will be brought out in the following specification and particularly set forth in the subjoined claims.

In the accompanying drawings, Figure 1 40 is a side elevational view of my improved jack. Figure 2 is a front elevational view thereof. Figure 3 is a longitudinal sectional view taken through the ball and spring construction for holding the slide in its upper or lower position. Figure 4 is a side elevational view of one of the laminated pawls. Figure 5 is a side elevational view of said jack with the side plate removed to show the lifting devices in their bar raising positions. Figure 6 is a side elevational view of 50 said jack with the side plate removed, showing the bar lowering position of said lifting devices. And Figure 7 is a side elevational view of a plunger and spring, with its cylindrical housing in section.

Throughout the specification and draw-

ings, similar reference characters denote corresponding parts.

Referring to the accompanying drawings, the numeral 1 designates a base having a 60 central opening adapted to receive the lower end of a tubular standard 2 around whose bottom portion are turned up, and suitably secured thereto, a series of triangular flanges 3. (See Figures 1 and 2.)

Vertically movable within the tubular standard 2 is a lifting bar 4 to the upper end of which is secured a concave head 5. Formed along the front and rear sides of the lifting bar 4 is a series of downwardly-pointed ratchet teeth 6 in zigzag or interstepped arrangement with each other. In other words, a tooth on one side is on a horizontal line that would pass midway between two teeth on the opposite side. This zigzag 75 toothed bar, co-operating with the double-gear construction to be hereinafter described, permits the bar to be raised $\frac{1}{16}$ ths of an inch, or lowered $\frac{1}{16}$ ths of an inch, on every up or down stroke of the lever respectively, 80 thus approximately doubling the lifting power of the jack over that of the one shown in my beforementioned patent. This zigzag arrangement of the teeth on the bar 4, also permits the bar to be dropped into the standard 85 after the weight has been removed from it.

The staggered ratchet teeth 6 are adapted to be engaged by a pair of upwardly pointed lifting pawls 7 pivotally supported within the following described frame construction provided on the upper part of the standard 2. As shown in Figure 4, each pawl 7 is constructed of laminations whereby it may be made in the punch press to cheapen its 95 manufacture.

Preferably screwed to each side of the upper portion of the tubular standard 2, is a fan shaped plate 8. To the lower middle portion of each plate 8 there is pivotally secured, by means of a pin 9, a toothed sector 10, which is laminated in order to cheapen its construction. (See Figures 1 and 2.)

Each laminated toothed sector 10 has a rearwardly projecting portion 11, and between these portions 11 there is secured a short shaft 12 upon which one of the lifting pawls 7 is loosely mounted. A similar shaft 12 is secured between the front ends of the sectors 10, to form a pivot for the other lifting pawl 7. These two shafts 12 loosely project through arcuate slots 13 provided in

each one of the plates 8 to allow said shafts, and the pawls 7 which they carry, an up and down movement when the sectors 10 are given an oscillatory movement by the means 5 now to be described.

Loosely mounted on a shaft 14 secured between ears 15 on the plates 8, are two laminated sectors 16 whose teeth engage the teeth of the sectors 10. The inner lamination of each sector 16 is turned inwardly and forwardly to form together a stem that receives a sleeve 17 in which may be readily inserted, a handle 18. In the inner end of the sleeve 17 there is a plug 19 to prevent the handle 18 from being thrust through it during insertion, said plug being held in place by two inwardly turned integral fingers 20 on the sleeve, that also assist in holding the latter on the stem formed by 10 the inner laminations of the sectors 16. (See Figures 1, 5 and 6.)

For the purpose of co-operating with the zigzag toothed bar in raising heavy loads, the sectors 16 and 10 are so disposed as to 25 have a gear ratio of two to one respectively.

In order to cause the pointed ends of the lifting pawls 7 to engage the ratchet teeth 6 of the lifting bar 4 to raise it when the jack lever is operated, the following construction 30 is provided. Referring to Figures 1, 5 and 6, there is provided on one side of the standard 2 between it and a respective side plate 8, a vertically movable slide 20. The latter comprises two flat vertical members 35 21 that are secured at their bottom ends to a transverse member 21^a having a central recessed portion that enables it to clear, for a short distance during its upward movement, the downwardly projecting tongue 40 part 22 of the side plate 8. (See Figure 1.)

Each vertical member 21 of the slide 20 has an upper and a lower longitudinal slot 23 and 24 respectively. Through the upper slots 23 there project large headed guide 45 pins 25 secured to the inner portion of the plate 8, while similar guide pins 26 project inwardly from said plate through the lower slots 24 in the vertical members 20. Each vertical member 21 also has a middle inwardly projecting ear 27 to which is secured, at right angles thereto, a small cylinder 28. Within each cylinder 28 is a plunger 29 adapted to be forced into engagement with the rear surface of a respective yawl 7 by a coil spring 30 within the rear portion of the cylinder. (See Figures 5, 6 and 7.)

For the purpose of raising and lowering the slide 20 to bring the plungers 29 into engagement respectively with the upper and lower surfaces of the pawls 7, an outwardly projecting cylinder 31 is secured to the middle portion of the transverse portion 21^a of the slide. Seated within this cylinder 31 is 65 a coil spring 32 adapted to force a ball 33

70 into an upper concave recess 34, or a lower concave recess 35, of the standard 2 to hold the slide 20 in its uppermost or lowermost position respectively. (See Figures 1, 2 and 3.)

When the ball 33 is in the upper recess 34 of the standard 2, the pawls 7 are in the proper position to elevate the lifting bar 4. Now when the operator reciprocates the handle 18, the sectors 16 will impart an oscillatory movement to the sectors 10, which in turn will reciprocate the shafts 12 to carry the pawls 7 up and down. During the upward movement of one pawl, its nose portion will be forced into engagement with a tooth 6 on the bar 4 by its respective plunger 29, since the slide 20 in its upper position brings the pressure of the plunger against the upper portion of the pawl. During this upward movement of one pawl 7, 85 the other one will be lowered by its respective shaft 12, with its nose portion riding idly over the teeth on the bar 4, and vice versa, as the operating lever is moved from one extreme position to the other. During 90 each up and down movement of the operating handle 18, the bar 4 will be raised, since when one pawl is traveling downward, the other one is being carried upward in engagement with a tooth on its respective 95 side of the bar 4.

When it is desired to lower the load, the cylinder 31 may be struck from above by the removed handle 18 or other instrument, to force the slide 20 downwardly to the position in which the ball 33 will rest within the recess 35 in the standard 2. It is thus unnecessary for one to stoop down to lower the slide with the hand.

When the slide 20 is in its lowermost position, the load carried by the bar 4 is lowered as follows. Referring to Figures 1, 2, 5 and 6, a transverse pin 36 is secured between the side plates 8 above the beveled nose portion of each pawl 7. When the slide 20 is in its 110 lowermost position, the plungers 29 will have transferred their pressure to the lower rear portions of the pawls 7. As the beveled nose portion of each pawl 7 passes under a respective pin 36, it will be forced by it, instead of 115 a plunger 29, into engagement with a tooth 6 on its respective side of the lifting bar. If the weight of the load upon the lifting bar 4 is approximately five pounds, it will be sufficient to cause the nose portion of the pawl 120 to be held in engagement with the tooth to sustain the descending load, since a load of that weight will be sufficient to hold the pawl and tooth in engagement against the pressure exerted on the lower end of the pawl 125 by its respective plunger 29. And when that particular pawl has reached its extreme lower position, the nose portion of the other one will be forced, by its respective pin 36, into engagement with a tooth on its side of the 130

lifting bar 4 to receive the weight of the load. At this point the plunger 29 that presses against the lower end of the first named pawl, will exert its force against the 5 lower end of said pawl to withdraw its upper end from engagement with the ratchet tooth 6, since the weight of the load has now been transferred to the other pawl.

It will now be seen that the nose portion of 10 one pawl will remain in engagement with a tooth on its respective side of the lifting bar 4 to sustain the weight of the load until the operating handle 18 reaches one extreme 15 position, whereupon the other pawl will be forced into engagement with a tooth on its respective side of the lifting bar 4 and let the weight down still further during the movement of the handle to its other extreme position, this alternate operation being continued 20 until the lifting bar 4 is completely relieved of its load. After this point is reached and the handle is brought to a horizontal position, the lifting bar 4 will drop to its normal position, since there is no weight upon it to 25 hold its teeth 6 in engagement with the nose portions of the pawls. Likewise, the lifting bar may be as speedily lifted to the load without operating the sector mechanism.

It will thus be seen that I have provided 30 an extremely powerful quick-action jack in which the number of parts have been reduced to the minimum. The small number of parts, together with the laminated construction of many of them, enables the jack to be produced cheaply without sacrificing its efficiency. It is convenient in operation, for it may be actuated by one in a standing position through a handle inserted in the sleeve 17. Nor is it necessary for one to stoop down to 40 move the slide 20 with the hand to its lowermost position when it is desired to lower the load, for this may be done by striking the cylinder 31 a blow with the removed handle 18 or other instrument.

45 Having described my invention, I claim:

1. In a jack, the combination with a tubular standard, of a lifting bar therein having ratchet teeth on two opposite sides, the teeth on one side of said bar being disposed in zig-zag relation to the teeth on the other side of said bar, lifting elements for alternately engaging the teeth on said bar, and reduction gear means for imparting an alternate up and down movement to said lifting elements 50 to raise the lifting bar, said reduction gear means and the zigzag disposed teeth on the lifting bar co-operating to lift a heavy load.
2. In a jack, the combination with a tubular standard, of a lifting bar therein having ratchet teeth on two opposite sides, a frame secured to said standard, a pair of toothed members pivotally secured to said frame, a pair of lifting pawls pivotally mounted between the toothed members, for alternate 55 movement thereby into engagement with the

teeth on the lifting bar to raise it, a second pair of toothed members in engagement with the first pair, and a handle for imparting an oscillatory movement to the second pair of toothed members, and through them to the 70 toothed members of the first pair, to give an alternate up and down movement to the pawls for the purpose specified.

3. In a jack, the combination with a tubular standard, of a lifting bar therein having ratchet teeth on two opposite sides, a frame secured to said standard, a pair of sectors pivotally secured to said frame, a pair of lifting pawls pivotally secured between said sectors, for alternate movement thereby into 75 engagement with the teeth on the lifting bar to raise it, a second pair of sectors in engagement with the first pair, and a handle for imparting an oscillatory movement to the second pair of sectors, and through them to 80 the sectors of the first pair, to impart an alternate up and down movement to the pawls for the purpose specified.

4. In a jack, the combination with a tubular standard, of a lifting bar therein having ratchet teeth on two opposite sides, a frame secured to said standard, a pair of oppositely disposed lever elements fulcrumed to said frame, a shaft secured between said lever elements on each side of the fulcruming 95 means, a pawl loosely mounted on each shaft, adapted to be given an up and down movement when the lever elements are reciprocated, a vertical slide within said frame, and a pair of spring pressed plungers carried by 100 said slide, for movement into engagement with the upper portions of said pawls to hold their nose portions in engagement with the teeth of said lifting bar, whereby the latter may be raised when the lever elements are 105 reciprocated.

5. In a jack, the combination with a tubular standard, of a lifting bar therein having ratchet teeth on two opposite sides, a frame secured to said standard, a pair of oppositely disposed lever elements fulcrumed to said frame, a shaft connected between said lever elements on each side of the fulcruming means, a pawl loosely mounted on each shaft, adapted to be given an up and down 115 movement when the lever elements are reciprocated, a vertical slide within said frame, a pair of oppositely-disposed ears on said slide, a cylinder secured to each ear at right angles thereto, a plunger in each cylinder, 120 and a spring in each cylinder adapted to press the plunger therein, into engagement with the upper rear portion of a respective pawl, to hold the nose portion thereof in engagement with the teeth on the lifting bar, 125 whereby the latter may be raised when the lever elements are reciprocated.

6. In a jack, the combination with a tubular standard, of a lifting bar therein having ratchet teeth on two opposite sides, a frame 130

- secured to said standard, a pair of pawls within said frame, means adapted to give said pawls an alternate up and down movement, a slide vertically movable within said frame, and compression means carried by said slide, adapted to automatically exert an inward force upon the upper and lower rear portions of said pawls when the slide is raised and lowered, to hold the nose portions of the pawls in engagement with the teeth on the lifting bar in the first instance and out of engagement therewith in the second instance.
7. In a jack, the combination with a tubular standard, of a lifting bar therein having ratchet teeth on two opposite sides, a frame secured to said standard, a pair of pawls within said frame, a pair of guide pins secured within said frame, a pair of vertically movable members within said frame provided with longitudinal slots through which said guide pins project, a transverse actuating bar secured to the bottom ends of the vertical members, a pair of oppositely-disposed ears on said vertical members, a cylinder secured to each ear at right angles thereto, and compression elements with said cylinders adapted to automatically exert an inward force upon the upper and lower rear portions of said pawls when the vertical members are raised and lowered, to hold the nose portions of the pawls in engagement with the teeth on the lifting bar in the first instance and out of engagement therewith in the second instance.
8. In a jack, the combination with a tubular standard, of a lifting bar thereon having ratchet teeth on two opposite sides, a frame secured to said standard, a pair of pawls within said frame, means adapted to give said pawls an alternate up and down movement, a slide vertically movable within said frame, compression means carried by said slide, adapted to automatically exert an inward force upon the upper and lower rear portions of said pawls when the slide is raised and lowered, and a spring pressed plunger carried by said slide adapted to enter an upper and a lower recess in the outer surface of the standard, to hold said slide in its upper and lower positions respectively for the purpose specified.
9. In a jack, the combination with a tubular standard, of a lifting bar thereon having ratchet teeth on two opposite sides, a frame secured to said standard, a pair of pawls within said frame, means adapted to give said pawls an alternate up and down movement, a slide vertically movable within the frame, compression means carried by said slide, adapted to exert an inward force upon the upper and lower rear portions of said

pawls when the slide is raised and lowered, an outwardly projecting cylinder on said slide adapted to be struck by an instrument to raise and lower the latter, and a spring-pressed plunger within said cylinder adapted to enter an upper and a lower recess in the outer surface of said standard, to hold said slide in its upper and lower positions respectively until said plunger is withdrawn from one of said recesses by a blow on the cylinder.

10. In a jack, the combination with a tubular standard, of a lifting bar, means for lifting and lowering said bar, a slide for adjusting said means in their raising or lowering positions, an outwardly projecting cylinder on said slide adapted to be struck by an instrument to raise and lower the latter, and a spring-pressed plunger within said cylinder adapted to enter an upper and a lower recess in the outer surface of said standard, to hold said slide in its upper and lower positions respectively until said plunger is withdrawn from one of said recesses by a blow on the cylinder.

11. In a jack, the combination with a tubular standard, of a lifting bar therein having ratchet teeth thereon, a frame secured to said standard, a pair of laminated toothed members pivotally secured to said frame, pawls carried by said toothed members for engagement with the teeth on said lifting bar to raise it, a second pair of laminated toothed members in engagement with the first pair, the inner laminations of the second pair of toothed members terminating in an outwardly projecting stem, a handle-receiving sleeve on said stem, a plug in the front end of said sleeve, and curved fingers on said sleeve adapted to hold the latter on the stem and to limit the inward movement of said plug.

12. In a jack, the combination with a tubular standard, of a lifting bar therein having ratchet teeth on two opposite sides, a frame secured to said standard, a pair of sectors pivotally secured to said frame, a second pair of sectors pivotally secured to said frame in engagement with the first pair of sectors, a pair of laminated pawls adapted to be carried by the first sectors into alternate engagement with the teeth on the lifting bar to raise it, and a slide within said frame for transferring pressure from the upper to the lower rear portions of said pawls for the purpose specified.

In testimony whereof I have hereunto set my hand this 7th day of September, 1920.

ALEXANDER W. MARR.

Witness:

HOWARD S. SMITH.
